[57] **CLAIM**

The ornamental design for a solderable mount for an electronic device, as shown and described.

DESCRIPTION

FIG. 1 is a front, top and right side perspective view of a solderable mount for an electronic device showing my new design;

FIG. 2 is a top plan view thereof;

FIG. 3 is a bottom plan view thereof;

FIG. 4 is a left side elevational view thereof, the right side elevational view being identical; and

FIG. 5 is a front elevational view thereof, the rear elevational view being identical.
